UNITED STATES PATENT OFFICE.

WILLIAM A. WHITE AND JAMES MCDONALD, OF NEW YORK, N. Y.

LIQUID-FUEL BURNER.

1,194,106.

Specification of Letters Patent. Patented Aug. 8, 1916.

Application filed April 19, 1915. Serial No. 22,229.

To all whom it may concern:

Be it known that we, WILLIAM A. WHITE, a citizen of the United States, and JAMES MCDONALD, a subject of King George V, both residents of the borough of Manhattan, in the city, county, and State of New York, have invented certain new and useful Improvements in Liquid-Fuel Burners, of which the following is a specification.

10 This invention relates to liquid fuel burners, and it has particular reference to the employment in a furnace such as used in heating buildings of a burner capable of efficiently consuming heavy hydrocarbons like

15 fuel oil.

Our improved burner is based upon the principle of the continual supply of a film of liquid fuel upon a horizontal support, laterally confined, and burning under the influence of a central draft of air, which is deflected and regulated to a point where self propagation of the flame provides complete combustion of the fuel and air mixture.

As an example of the practical carrying out of our invention we may employ a circular plate, horizontally disposed, having a central orifice for the uptake of air, and having its upper surface bounded with upstanding, concentric walls about its inner and outer perimeters. Said plate may support a layer or film of liquid fuel, entered thereon as through an aperture in said plate, and supplied thereto as by gravity feed, the fuel being preferably localized upon the plate

25 near the central orifice therein by one or a series of annular, shallow depressions or grooves thereon; a fuel overflow being provided as by an aperture through the outer concentric wall to prevent the fuel head

30 from rising unduly.

Extending over the air uptake orifice is a mushroom or disk valve, which also lies in the path of the ascending flame, said valve having means of vertical adjustment relatively to the burner plate, whereby the angle of deflection and speed of air entering through the uptake may be regulated, and the intensity of the flame propagation duly governed.

45 The burner aforesaid may be housed within a furnace of any suitable character, either for supplying heated air through the usual channels, or for heating water, or generating steam, the methods of installation and

arrangement being only such as fall within 55 the province of mechanical expediency.

Other features and advantages of our invention will be hereinafter described.

In the drawing: Figure 1 is a vertical sectional view of an apparatus embodying the 60 principles of our invention, and Fig. 2 is a section on the line 2—2 of Fig. 1.

The structure illustrated in the drawing presents a simple form of apparatus involving elements arranged for the efficient combustion of liquid fuel in the manner established by our improvement, in which structure the burner is seen to be composed of a horizontal plate 1 of circular or disk form, with an outer retaining wall 2 extending upwardly from the periphery of said plate, and around said plate; together with a central orifice, occupied by a draft tube 3, whose upper portion protrudes through plate 1, there forming an inner, concentric wall 4. 70 One or a number of concentric grooves or shallow depressions 5 are provided in the upper surface of plate 1, near the inner wall 4, the innermost of said grooves being in communication, as through the plate, with 80 a feed pipe 6, which is extended upwardly, outside the burner, and may have a reception cup 7, with a filter 8, which may be located in position to receive liquid fuel as from a source of supply 9, through a faucet 85 or valve 10.

A mushroom or disk valve 11 lies over the draft tube 3, also extending over the grooves 5, and is mounted upon a stem 12, which is guided for vertical movement by bearings 90 13 formed in spiders 14 supported in the draft tube 3, said stem having means of adjustment such as a rack 15, with which is engaged an actuating pinion 16.

The burner aforesaid may be housed with 95 in a furnace of any suitable character for its practice, such housing being here only diagrammatically indicated by the dotted lines 17.

In the operation of our improved burner 100 for liquid fuel, fuel is admitted to a groove 5 through the pipe 6, as by opening the valve 10, and is ignited in said groove. Air to support combustion of the fuel enters 105 through the tube 3 under the natural draft of the furnace in which the burner is installed, this air striking against the under surface of the valve 11, and being deflected

thereby, more or less acutely, according to the vertical position of adjustment of said valve relatively to plate 1, which adjustment also serves to vary the air speed and volume, and thus to regulate the flame propagation to the point of complete combustion.

The fuel feed is regulated at the faucet or valve 10, whereby a constant gravity flow may be provided in one or more of the 10 grooves 5, the overflow from one groove entering the next adjacent groove, and so on. Should an excess of fuel pass from the grooves 5 on to the surrounding portion of the plate 1, any unburned excess may pass 15 off through a waste pipe 18, from whence it may be returned to the source of supply or otherwise disposed of.

Variations may be resorted to within the spirit and scope of our said invention, and 20 parts thereof used without others.

We claim:—

1. A liquid fuel burner comprising a plate having a central draft orifice, and a depression in the inner portion of said plate to 25 localize the fuel thereon, said plate also having an extended fuel supporting surface, and a valve in the path of the burning products.

2. A liquid fuel burner comprising a plate having a central draft orifice, and a depression in the inner portion of said plate to 30 localize the fuel thereon, said plate also having an extended fuel supporting surface, in combination with fuel feed means, and a valve in the path of the burning products.

3. A liquid fuel burner comprising a plate having a central draft orifice, and a depression in the inner portion of said plate to 35 localize the fuel thereon, said plate also having an extended fuel supporting surface, in combination with an adjustable valve in 40 the path of the burning products.

4. A liquid fuel burner comprising a plate having a central draft orifice, and a depression in the inner portion of said plate to 45 localize the fuel thereon, said plate also having an extended fuel supporting surface, in combination with regulating fuel feed means, and an adjustable air admission valve in the path of the burning products.

5. A liquid fuel burner comprising a horizontally disposed plate, a draft tube extending centrally therethrough, a concentric fuel receiving groove in the inner portion of said plate about said draft tube, to localize the 55 fuel upon the plate, and to form a restricted flame zone relatively to the area of said plate, a gravity fuel feed in communication with said groove, and means for regulating the admixture of air to support combustion 60 of the fuel.

6. A liquid fuel burner comprising a horizontally disposed plate, a draft tube communicating centrally therewith, means for supplying fuel to said plate, an annular depression upon the inward portion of the

plate to localize the fuel thereon and form a restricted flame zone relatively to the area of said plate, and means for deflecting the air entered through said draft tube to mix with the burning fuel.

70

7. A liquid fuel burner comprising a horizontally disposed plate, a draft tube communicating centrally therewith, means for supplying fuel to said plate, inner and outer, concentric, fuel retaining walls for said 75 plate, an annular depression upon the inward portion of the plate to localize the fuel thereon and form a restricted flame zone relatively to the area of said plate, an overflow outlet, and means for deflecting the air 80 entered through said draft tube to mix with the burning fuel.

80

8. A liquid fuel burner comprising a horizontally disposed plate, a draft tube communicating centrally therewith, an annular 85 depression upon the inward portion of the plate to localize the fuel thereon and form a restricted flame zone relatively to the area of said plate, and an air deflecting valve extending over said draft tube and flame zone. 90

9. A liquid fuel burner comprising a horizontally disposed plate, a draft tube communicating centrally therewith, an annular depression for localizing fuel over a central, restricted, annular portion of said 95 plate, to form a flame zone, a disk valve extending over said draft tube and flame zone to deflect air, rising through said draft tube, downwardly into said flame zone, and means for adjusting said disk valve vertically to 100 regulate the air volume and its speed of travel.

100

10. The combination with a furnace of a liquid fuel burner therefor comprising a fuel supporting plate having a central draft 105 orifice and inner and outer, concentric, fuel confining walls, a depression in the inner portion of said plate to localize the flame zone around said orifice and retard the fuel from spreading over the outward portion of said plate, fuel feed means for said depression, and a disk valve to deflect air of combustion 110 into said flame zone.

110

11. The combination, with a furnace, of a liquid fuel burner therefor, comprising a horizontally disposed plate, an outer fuel retaining wall therefor, said wall having an overflow outlet, a central draft tube protruding upwardly through said plate, to form an inner fuel retaining wall, an annular fuel localizing depression in the surface of said plate, near said inner wall, means communicating fuel to said depression, and a disk valve extending over said draft tube and depression. 115

115

12. The combination, with a furnace, of a liquid fuel burner therefor, comprising a horizontally disposed plate, an outer fuel retaining wall therefor, said wall having an overflow outlet, a central draft tube pro- 120

120

truding upwardly through said plate, to form an inner fuel retaining wall, an annular fuel localizing depression in the surface of said plate, near said inner wall, 5 means communicating fuel to said depression, and a disk valve extending over said draft tube and depression, the under surface of said disk valve being concaved, to deflect the rising air downwardly into the flame 10 zone.

13. A liquid fuel burner comprising a horizontally disposed plate to support an even film of fuel, a confining wall having an

outlet, said plate having a central air supply with concentric fuel localizing means adjacent thereto, means supplying fuel by gravity flow to said localizing means, and an air controlling valve in the path of the flame. 15

Signed at the borough of Manhattan, in the city, county and State of New York, this 20 16th day of April, A. D. 1915.
